UNITED STATES PATENT OFFICE.

CHARLES STALLINGS, OF CHICAGO, ILLINOIS.

DESIGN FOR A POST-CARD.

41,188.

Specification for Design.

Patented Feb. 21, 1911.

Application filed October 10, 1910. Serial No. 586,410. Term of patent 7 years.

To all whom it may concern:

Be it known that I, CHARLES STALLINGS, a citizen of the United States, residing at Chicago, in the county of Cook and State of Illinois, have invented a new, original, and ornamental Design for Post-Cards, of which the following is a specification, reference being had to the accompanying drawing, forming a part thereof.

The figure is a plan view of a post card showing my new design.

My design consists of a post card having

the picture of a woman printed thereon and upon the figure the representation of a flower, the petals of which are formed of appropriately colored silk ribbon.

I claim:—

The ornamental design for a post card, as shown and described.

CHARLES STALLINGS.
